UNITED STATES PATENT OFFICE.

EDWIN COLWELL BLAKE AND ERNEST CLAYTON TRIMMELL, OF WORCESTER,
ASSIGNORS, BY MESNE ASSIGNMENTS, TO SAID BLAKE AND TRIMMELL,
AND GEORGE P. HUNT, OF BOSTON, MASSACHUSETTS.

ELECTRIC-CIRCUIT-WIRE INSULATOR.

SPECIFICATION forming part of Letters Patent No. 342,320, dated May 25, 1886.

Application filed February 25, 1886. Serial No. 193,183. (No model.)

To all whom it may concern:

Be it known that we, EDWIN COLWELL BLAKE and ERNEST CLAYTON TRIMMELL, of the city and county of Worcester, of the Commonwealth of Massachusetts, have invented a new and useful Improvement in Electric-Circuit-Wire Insulators; and we do hereby declare the same to be described in the following specification, and represented in the accompanying drawings, of which—

Figure 1 is a top view, Fig. 2 a broad side elevation, Fig. 3 a narrow side view, and Figs. 4 and 5 are a vertical, transverse, and median sections, of an insulator provided with our invention, the nature of which is defined in the claims hereinafter referred to. The plane of section of the said Fig. 4 is through the two opposite middle notched ears, while the plane of section of Fig. 5 is at right angles to that of Fig. 4.

We are aware that it is not new to construct a telegraph-circuit-wire insulator with three ears extending upward from its top and having grooves or channels in them to receive the wire, all being arranged and formed as represented in the United States Patent No. 154,451, dated August 25, 1874.

In carrying out our improvement we have two sets of such ears, one set being on one side and the other on the opposite side of the body of the insulator, such body and ears being integral or in one piece of glass or other suitable non-conductor of electricity. One ear of each set is midway between the two others, such median ear being notched upward, and each of the others of the set being notched downward. The wire, when held by a set of the ears, goes through these notches and under and against the middle ear and over and rests upon the two outer ears of the set. Between the two sets of ears the upper surface of the insulator is shaped very like that of a riding-saddle—that is to say, it is concave lengthwise, as represented—such being in order to enable it to discharge either rain or melting snow laterally off opposite sides of the insulator without causing it to flow down upon either of the wires or their sustaining sets of ears,

all being as represented in the said drawings, in which—

A is the body of the insulator, such body on its upper part being a quadrilateral prism, and in its lower part, *e*, a cylinder. The three notched ears of each of two opposite sides of the prism *a* are shown at B, B', and B, they being arranged and formed as represented. The body is cup-shaped or concave at its lower end, as shown at *g*, and from the concavity upward within the body and concentric with the external surface of the cylindrical part *e* there extends a cylindrical chamber or socket, *h*, provided with two pointed lugs or projections, *i k*, they projecting from its inner curved surface, one of such lugs being a little higher than the other. The arrangement of a wire in each set of ears is exhibited at *l* in dotted lines. The crown or upper surface of the body A is curved concavely, as shown in Fig. 2 at *a b c*, and laterally in Fig. 5 at *d b d*, such being for the purpose hereinbefore stated.

Our insulator will support two electric circuit-wires and protect them, in a measure, from water that may result from melting of ice or snow that may gather on the top of the insulator. When the ears project upward from the top of the insulator, and the wire is curved between them and over and upon such top, they operate to hold on the top snow that may fall or ice that may form there, which on melting and running down the side of the body is likely to produce icicles, that, extending from the wire to the supporting-post, are liable to affect the proper insulation of such wire. With our concave or saddle-shaped top to the body and arrangement of the two sets of ears on opposite sides of such body, the snow or ice will not easily gather on the ears and upon the parts of the wires in them. Such snow or ice on melting will be readily discharged without the water from it falling upon the ears or the wires held by them.

We do not claim an electric-wire insulator having a set of three ears projecting upward from its top, as shown in the aforesaid patent; nor do we claim an electric-wire insulator having on one side only of it a set of three or more

of such ears, such being as shown in the United States Patent No. 76,358, for when the ears are on but one side of the insulator but one wire can be supported by it, and such wire, by the strains it brings upon the insulator, tends to loosen or injure its support, whereas when the insulator has sets of ears projecting from opposite sides of it and to sustain two wires, one wire balances the other, and there is no lateral strain tending to break the insulator or its connection with its post of support. Therefore

We claim—

1. An electric-circuit-wire insulator having on each of two opposite sides of its body a set

of three notched ears arranged with each other, substantially as set forth.

2. An electric-circuit-wire insulator having on each of two opposite sides of its body a set of three notched ears arranged with each other as set forth, and having the top of such body, where between the two sets of ears, concave, substantially as represented.

EDWIN COLWELL BLAKE.
ERNEST CLAYTON TRIMMELL.
